United States Patent

Des. 236,099
Patented July 29, 1975

236,099

SAILBOAT

Ervin R. Heald, Los Alamitos, William D. Kelly, Mission
Carlsbad, Calif. 92008

Filed Jan. 7, 1974, Ser. No. 431,163

Term of patent 14 years

Int. Cl. D12—06

U.S. Cl. D12—64

*FIG. 3**FIG. 4**FIG. 5*FIG. 1 is a side elevational view of the sailboat with an indication by a line underneath of the various points at which the half sections of FIG. 5 are taken.

FIG. 2 is a top plan view of FIG. 1.

FIG. 3 is an elevational view from the bow.

FIG. 4 is an elevational view from the stern.

FIG. 5 shows hull half sections as traditionally prepared by naval architects with the station numbers corresponding to the numbers of FIG. 1. The port side of the boat is substantially identical in appearance to the starboard side shown in FIG. 1.

What is claimed is:

The ornamental design for a sailboat, substantially as shown and described.
